UNITED STATES PATENT OFFICE.

ERNESTO GIUSEPPE PONTI, OF TURIN, ITALY.

RUBBER NOZZLE FOR CLINICAL AND LIKE PURPOSES.

Application filed January 26, 1927, Serial No. 163,745, and in Italy January 30, 1927.

My invention has for its object a rubber nozzle adapted to fit through its larger end mouthpiece the neck of a bottle, flask, or the like, and provided with an external passage for the blowing off of the air. My invention aims to provide a nozzle which will allow the liquid in the bottle or the like to uniformly flow therefrom, when the bottle is turned upside-down, while avoiding any whirlings, bubblings, eddyings or turbulence of the liquid at the outlet of the nozzle, so that the liquid will flow with continuity and as uniformly as possible.

Besides generical, technical or laboratory applications, a nozzle according to my invention is particularly adapted for medical purposes, such as irrigations, clysters, and the like, requiring the use of sterile and aseptic liquids. For this purpose, I fit the nozzle on the mouthpiece of the bottle (burette, Florence flask, or the like) used for boiling water and/or dissolving chemicals or the like, and then I slip a usual rubber hose over the nozzle outlet, so that I may immediately utilize the bottle or the like for irrigations or clysters, without pouring the liquid from its container to any other non-sterilized receptacle, thus operating under the best aseptic conditions.

An embodiment of my invention is shown by way of example in the annexed drawing. Fig. 1 is a side view, Fig. 2 a vertical sectional view of the improved nozzle in operative position, while Figs. 3 and 4 are cross sectional views thereof.

My improved nozzle comprises a cylindrical neck portion 1 adapted to fit the neck or mouthpiece 2 of a bottle, flask, or the like, an enlarged belly 3 in which opens a narrow side passage 4, and an outlet 5 having a flanged edge for receiving and retaining a connection to the hose.

Passage 4 ends externally with an enlarged funnel-shaped mouthpiece, wherein it is advisable to enter a lump of filter wadding or gauze.

Subsequent to the enlargement in section of belly 3, the throttling of outlet 5 and the relatively very narrow passage 4, the latter merely acts as an air blast or exhauster, for the admission of the exact amount of air required to replace the discharge liquid, while the latter is flowing off through the outlet 5 and the irrigation hose, not shown.

Any burette, flask, or the like, adapted for boiling liquid therein, may be fitted with my improved nozzle over its mouthpiece, to be directly utilized, by merely reversing it upside-down, for any clinical, laboratory, or like purposes, without pouring the sterilized liquid therefrom.

What I claim is:

1. A rubber nozzle of the character set forth, comprising a cylindrical neck portion, an enlarged belly, a narrow air passage at the side of the neck and opening in said belly, a tubular outlet member for connection of said belly portion to a rubber hose, and an enlarged funnel-shaped inlet at the opposite or outer end of said narrow passage.

2. A rubber nozzle comprising a hollow body having at one end a cylindrical neck adapted to fit upon the neck of a bottle, a reduced tubular outlet at its other end adapted to receive a hose, an enlarged portion between the neck and outlet, and an air passage leading from the outer end of the neck into the enlarged portion, the outer end of said passage being enlarged to adapt it to receive a filtering material.

In testimony whereof, I affix my name this 8th day of January, 1927.

ERNESTO GIUSEPPE PONTI.
